DESIGN FOR A MERCHANTISE DISPLAY
CABINET

Ralph E. Eckberg, deceased, late of Seattle, Wash., by Gwendolyn Eckberg, executrix, Seattle, Wash.

Application September 6, 1939, Serial No. 87,069

Term of patent 7 years

To all whom it may concern:

Be it known that Ralph E. Eckberg, deceased, late a citizen of the United States and a resident of Seattle, in the county of King and State of Washington, did invent a new, original and ornamental Design for a Merchandise Display Cabinet, of which the following is a specification, reference being had to the accompanying drawing forming a part thereof.

In the drawing:

Fig. 1 is a front elevational view of a merchandise display cabinet, showing the design;

Fig. 2 is a side elevational view, looking in the direction of the arrows of line 2—2 of Fig. 1;

Fig. 3 is a top plan view, looking in the direction of the arrows of line 3—3 of Fig. 1; and

Fig. 4 is a perspective view thereof.

I claim:

The ornamental design for a merchandise display cabinet, as shown.

GWENDOLYN ECKBERG,

Executrix of the Last Will and Testament of Ralph E. Eckberg, Deceased.
